UNITED STATES PATENT OFFICE.

WILLIAM H. PHEASANT, OF McCLURE, PENNSYLVANIA, ASSIGNOR OF ONE-HALF TO ORIE A. CRAWFORD, OF McCLURE, PENNSYLVANIA.

JAR OPENER AND CLOSER.

No. 845,118.

Specification of Letters Patent.

Patented Feb. 26, 1907.

Application filed November 22, 1904. Serial No. 233,919.

To all whom it may concern:

Be it known that I, WILLIAM H. PHEASANT, a citizen of the United States, residing at McClure, in the county of Snyder and State of Pennsylvania, have invented a new and useful Jar Opener and Closer, of which the following is a specification.

This invention is a household tool designed to be used for opening and closing the screw-tops of jars and cans, the object of the invention being to provide a cheap, simple, and efficient device and one which can be easily arranged and operated, a movement in one direction serving to grip the top and turn it in one direction and a movement in the opposite direction causing it to grip the top and turn it in the opposite direction.

The invention consists in the novel features of construction and combination hereinafter fully described, and pointed out in the claim.

In the drawings, Figure 1 is a perspective view showing the practical operation of my invention. Fig. 2 is a top plan view of the tool, the jar-top being shown in dotted lines; and Fig. 3 is an edge view of the tool.

In constructing a tool in accordance with my invention I employ a handle A, having a broad flattened round inner end A', to which are pivotally connected the curved fingers or plates B and C, said fingers or plates being pivoted at B' and C' upon opposite sides of the longitudinal diameter of the handle, and pivotally connected to the fingers or plates B and C are the curved plates D and E, respectively, the pivots being designated D' and E', and these members are pivoted at D' and E', thus providing a clamping-ring composed of sections and so connected to the handle that by placing the ring over the cap F of the jar G

and moving the handle in either direction the round end of the handle will be brought into engagement with the cap and the ring will be contracted and clamped to the cap and by continuing the movement the cap 45 can be screwed or unscrewed according to the direction of movement of the handle. As soon as the operation is completed the tool can be removed by bringing the handle back to a central position and lifting the ring from 50 the cap. If the cap is to be removed, the tool can be held clamped to the cap and used as a lifter after the cap has been unscrewed.

Having thus fully described my invention, what I claim as new, and desire to secure by 55 Letters Patent, is—

A jar opener and closer of the kind described, comprising a handle having a broad flattened rounded end, two flat curved plates pivotally connected to the flat end of the 60 handle, one on each side of the longitudinal center thereof, and in such position that the rounded end of the handle projects somewhat within the curve of the inner edges of the plates, two curved plates of greater 65 length pivotally connected together at one end, their other ends being pivotally connected to the free ends of the first-named plates, the broad surfaces of the said plates and handle lying in approximately the same 70 plane, whereby a flat ring is formed which is adapted to be clamped about the cap of a jar when the handle is turned in either direction so as to bring the projecting rounded end of said handle into engagement with the cap. 75

WILLIAM H. PHEASANT.
